CLAIM

The ornamental design for holder, as shown and described.

DESCRIPTION

FIG. 1 is a front, top, perspective view of a holder of my present invention.

FIG. 2 is a bottom, rear, perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The equal-length broken lines in the drawings depict portions of the holder that form no part of the claimed design. The dash-dot-dash lines define the boundaries of the claim.

1 Claim, 6 Drawing Sheets
